DRAPE SUPPORT

Robert R. De Ment, Cleveland, Ohio

Application March 14, 1940, Serial No. 323,956

9 Claims. (Cl. 45—106)

This invention relates to the art of drape supports used in connection with caskets for the purpose of providing a suitable background therefor.

The object of the present invention is to devise such a support in which the several parts are permanently connected together and may be readily collapsed and folded into compact form for convenience in transportation of the same.

More specifically, the object is to devise a collapsible support in which the base, uprights and drape-supporting bar or bars are connected together in a permanent manner and may be extended to occupy operative position or collapsed and folded into compact form when not in use, these adjustments being effected without disconnecting any of the parts.

Other objects will appear from the following description and claims when considered together with the accompanying drawing.

Fig. 1 is an elevation of my device in extended position;

Fig. 2 is a top plan view of the same;

Fig. 3 is an enlarged view taken on line 3—3 of Fig. 1;

Fig. 4 is an enlarged partial view of the top of the device and shows the arrangement of the parts; and

Fig. 5 is a detail view of the ring nut means for securing the sections of the collapsible uprights in extended position.

It is to be understood that the present form of disclosure is merely for the purpose of illustration and that there may be devised various modifications without departing from the spirit of my invention as herein set forth and claimed.

Referring now to the accompanying drawing in detail, the base 1 is of substantial dimensions and is provided with the parallel track grooves 2 and 3 which extend lengthwise of the base and substantially from end to end thereof. At the right-hand end of one track and at the left-hand end of the other track there are the upright casting 4 and 5, respectively, with tubular upwardly extending portions 4' and 5' opening inwardly toward each other for engagement of the lower part of the bottom section of the telescopic uprights 6 and 7, respectively, so as to hold the same in upright position, as will be explained.

Slidably engaged in the track grooves of the base are the two foot members 8 and 9 to which are pivotally connected the lower ends of the telescopic uprights 6 and 7 at the points 10 and

11. Each foot member comprises an inverted T-member 8' and 9', respectively, which has its lower horizontal portion engaged within the track groove for slidable movement therealong, 5 while the threaded pin 12 extends upwardly from the vertical portion of the inverted T-member, in each instance, so as to receive the wing nut 13. The split locking member 14 is adapted to fit down over the upright portion of the T-member 10 to permit the pin 12 to extend therethrough; so that upon tightening the wing nut 13, the member 14 will be forced downwardly against the base member while the horizontal part of the T-member will be pulled up against the inner 15 surface of the track groove, thereby firmly securing the foot member in set position. When so engaged after the telescopic upright supporting members have been extended, as indicated in Fig. 1, they will be securely held in such position. This, of course, is the position of the parts when the drape support is in use.

The collapsible uprights 6 and 7 each comprises three sections, according to the present form of illustration. These sections can be secured in extended position by means of the familiar ring nut 15 in each instance; and upon releasing this nut, the telescopic sections can be collapsed within each other, as will be readily understood.

30 The main transverse drape bar 16 at the top has the depending end portions which are pivotally connected to the ends of the top-most section of the telescopic upright, in each instance, and such connection is indicated by the 25 reference numeral 20.

The side arms 18 are pivotally connected to the vertical ends of the main transverse bar 16 and are adapted to be turned about a vertical axis so as to be placed in any desired position, either 40 in extension of the main drape bar or at any desired angle with respect thereto. The arms 18 are secured in position by means of the wing screws 17.

45 The end arms 19 are pivotally connected to the ends of the side arms 18 for adjustable turning movement about a vertical axis, thereby providing a still further extension for the support of the drape. The end arms are curved rearwardly although they may be given any other 50 desired form. The end arms 19 may be secured in desired position by means of the wing nuts 21.

The main drape bar is of double form, as indicated in Fig. 2, so as to permit a background drape to be suspended from the rear part thereof and a valance or the like to be suspended

from the front part thereof, thereby providing a combination of drapes which may be of different colors, as will be understood.

It will be observed that that main drape bar 16 is of substantially the same length as the base so that when the auxiliary arms 18 and 19 are folded inwardly, the device can be collapsed to occupy practically the same space as the length of the base. This is accomplished by loosening the nuts of the telescopic members and collapsing the same to substantially the height of the lower-most section of the upright in each case. Then, upon loosening the wing nuts 13, the foot members can be slid along the tracks in opposite directions, as indicated in dotted lines in Fig. 1, whereupon the foot members will pass each other and finally come to occupy positions at the opposite ends of the base from what they occupy when in upright position. This folding action is made possible by the pivotal connections between the upper ends of the uprights and the drape bar and also the pivotal connections between the bottom ends of the uprights and the foot members. If so desired, the wing nuts may be tightened after the device has been folded down into collapsed position in order to hold the parts more securely in such folded position.

It will be observed that the pivotal connections between the upper ends of the uprights and the drape bar and those between the bottom ends of the uprights and the foot members have their axes parallel to each other and transversely of the tracks, thereby permitting the manipulation above described.

In collapsing the device in the manner referred to, the drape can be folded in with the arms 13 and 19 and then folded in any suitable manner as the device is lowered into collapsed position, without removing the drape from the support. If so desired, the collapsed device can be placed in a container or case of proper size for transportation of the same. In fact, the entire base structure can be built into such a container as a permanent part thereof, although the base itself is alone sufficient to serve as a dependable means of support for the entire device. Or, only the castings at the ends of the base might be built in the container as a permanent part thereof and the tracks omitted entirely or some other suitable means adopted in the bottom of the case for guiding the lower ends of the uprights during the folding and unfolding adjustments, if so desired. However, it is preferred that the tracks or the equivalent thereof be included as part of the device so as to facilitate the manipulations in the manner above described.

The folding and unfolding operations, as above explained, can be performed in a simple manner and without any danger of injury to the hands of the user, and there is nothing to get out of order.

In referring to the connections between the several parts as being "permanent," this word is employed in the sense that these parts remain connected during the collapsing and extending of the device, although these parts might be removable from each other at any time desired so far as the present combination is concerned. Thus, for all intents and purposes of the present 70 device when operated in the manner described, the connections may be said to be permanent but without involving any complications or extraordinary hardships in the manufacture and assembly of the parts thereof.

What I claim is:

1. A drape support comprising a base of substantial length, a pair of foot members operatively connected to said base and mounted for 55 slidable movement past each other, each being slidable throughout substantially the entire length of said base, a pair of spaced uprights having pivotal connection at their lower ends with said foot members, and a horizontally disposed drape bar having pivotal connection with the top part of said uprights, said pivotal connections being about parallel axes transversely of the length of said base, whereby said uprights and drape bar may be folded down together upon said base, and 15 means for holding said uprights in upright position.
2. A drape support comprising a base of substantial length, a pair of foot members operatively connected to said base and mounted for 20 slidable movement past each other, each being slidable throughout substantially the entire length of said base, a pair of spaced collapsible uprights having pivotal connection at the lower end thereof with said foot members, and a horizontally 25 disposed drape bar having pivotal connection with the top part of said uprights, said pivotal connections being about parallel axes transversely of the length of said base, whereby said uprights may be collapsed and folded down with the drape bar upon said base, and means for holding said uprights in upright position.
3. A drape support comprising a base of substantial length, a pair of foot members operatively connected to said base and mounted for 35 slidable movement past each other, each being slidable throughout substantially the entire length of said base, a pair of spaced telescopically collapsible uprights having pivotal connection with said foot members, and a horizontally disposed 40 drape bar having pivotal connection with the top part of said uprights, said pivotal connections being about parallel axes transversely of the length of said base, and the length of said collapsed uprights and drape bar being substantially 45 the same as the length of said base, whereby said uprights may be collapsed and folded down with the drape bar upon said base, and means for holding said uprights in upright position.
4. A drape support comprising a base of substantial length, said base having a pair of parallel tracks extending substantially the entire length thereof, a pair of foot members each having permanent slide engagement with one of said tracks so as to be slidable past each other in opposite directions, a pair of spaced uprights each having permanent pivotal connection at its lower end with one of said foot members, and a horizontally disposed drape bar having permanent pivotal connection at its ends with the top part of said uprights, said pivotal connections being about parallel axes transversely of the 55 length of said base and of said tracks, whereby said uprights and drape bar may be folded down together upon said base, and means for holding said uprights in upright position.
5. A drape support comprising a base of substantial length, said base having a pair of parallel tracks extending substantially the entire length thereof, a pair of foot members each having permanent slide connection with one of said tracks so as to be slidable past each other in opposite directions, a pair of spaced telescopically collapsible uprights each having permanent pivotal connection with one of said foot members, and a horizontally disposed drape bar having 70 75

permanent pivotal connection at its ends with the top part of said uprights, said pivotal connections being about parallel axes transversely of said tracks, whereby said uprights may be collapsed and folded down with the drape bar upon said base, and means for holding said uprights in upright position.

6. A drape support comprising a base of substantial length, a pair of spaced collapsible uprights, a horizontally disposed drape bar having pivotal connection between its ends and the top of said uprights on axes transversely of the length of said base, upwardly extending means provided at the ends of said base for receiving and anchoring the lower ends of said uprights in upright position, said anchoring means having their inwardly facing sides open to receive the lower end portions of said uprights and being of sufficient vertical extent to hold said uprights in upright position, and means for securing said uprights in fixed position within said anchoring means, whereby the lower ends of said uprights can be released from said anchoring means and moved inwardly past each other along said base so as to collapse the same and at the same time cause said drape bar to be lowered into collapsed position thereupon.

7. A drape support comprising a base of substantial length, a pair of spaced collapsible uprights, a horizontally disposed drape bar having pivotal connection between its ends and the top of said uprights on axes transversely of the length of the base, upwardly extending means provided at the ends of said base for receiving and anchoring the lower ends of said uprights in upright position and being of sufficient vertical extent to hold said uprights in such position, and means for securing said uprights in fixed position within said anchoring means, whereby the lower ends of said uprights can be released and removed from said anchoring means and moved

past each other along said base so as to collapse the same and at the same time cause said drape bar to be lowered into collapsed position thereupon.

5 8. A drape support comprising a pair of spaced collapsible uprights, a horizontally disposed drape bar having pivotal connection between its ends and the top of said uprights on horizontal axes transversely of the length of said drape bar, upwardly extending means for receiving and anchoring the lower ends of said uprights in upright position, said anchoring means having their inwardly facing sides open to receive the lower end portions of said uprights and being of sufficient vertical extent to hold said uprights in upright position, and means for securing said uprights in upright position within said anchoring means, whereby the lower ends of said uprights can be released from said anchoring means and moved inwardly past each other so as to collapse the same and at the same time cause said drape bar to be lowered into collapsed position thereupon.
